UNITED STATES PATENT OFFICE.

WILLIAM KELLY, OF SARANAC, MICHIGAN.

FENCE.

SPECIFICATION forming part of Letters Patent No. 378,793, dated February 28, 1888.

Application filed April 16, 1887. Serial No. 235,035. (No model.)

To all whom it may concern:

Be it known that I, WILLIAM KELLY, of Saranac, in the county of Ionia and State of Michigan, have invented certain new and useful Improvements in Fences; and I do hereby declare that the following is a full, clear, and exact description thereof, reference being had to the accompanying drawings, and to the letters of reference marked thereon, which form part of this specification, in which—

Figure 1 is a perspective view of a portion of my improved rail fence. Fig. 2 is a side view of the same, showing the rods used in building the fence. Fig. 3 is a cross-section 15 of the fence on line xx , Fig. 2.

This invention relates to improvements in straight rail fences, and its objects are to improve the construction of the same, to render them self-bracing and rigid, and to lessen the 20 amount of material used in making them and consequent cost of same, as compared with the present construction of such fences, all of which objects are obtained by the means illustrated in the drawings, and hereinafter described, and particularly specified in the appended claim.

Referring to the drawings by letter, A A designate two rails forming the X-braces or supports of the fence in ordinary manner, except that they are crossed near their upper 30 ends and are set at such an angle to each other that a rail, B, can be laid on top between their upper ends and a rail, C, just below their point of intersection and below rail B, as shown, and yet be a proper distance apart to leave the ordinary space between the rails B C. The rails A A and B are tied together by wires a , as shown, and the rail C is similarly tied to rails A A, the rails B C being thus supported 35 by and bracing two adjoining pairs of rails A A, as shown.

D D designate short pieces on one side of the fence, which incline upward from the ground to points on the rails A, the pieces D standing in parallel planes with the rails B C and at right angles to the planes of rails A A, and the inclination of pieces D being such that their lower ends enter or rest upon the earth at a point distant from rails A about one-third 45 the length of rails C or B.

E E designate pieces similar but standing in opposite directions to pieces D and on op-

posite sides of rails B C therefrom, connecting with the rails A, opposite the rails A, to which pieces D are connected. The upper ends of 55 pieces D and E are secured to their respective rails A A by wires $d e$, as shown.

It will be observed that pieces D E brace the rails A A and prevent their lateral movement or swaying, in addition to the bracing 50 afforded by rails B C.

The pairs or brace-pieces D E for the pairs of rails A A preferably alternate—that is, for two adjoining pairs of rails A A the inner brace-pieces, D E, would be on the same side 65 of the fence and the braces E and D between one of these pairs of rails A A, and the next succeeding would be on the opposite side of the fence, as shown. The object of this is to keep the lower horizontal rails of the fence 70 parallel with and in the same vertical plane as rails B and C when the lower rails are connected to the adjoining but oppositely standing pieces D E, as shown.

F F designate horizontal rails corresponding in length to the rails B C, and secured below the same to the opposite brace-pieces, D E, as shown. Any number of rails F F may be employed, as may be desirable. The adjoining ends of the rails F in adjoining sections of the 80 fence are overlapped or side lapped to make the obstruction of the rails continuous. The rails F F are secured, by wires similar to wires $d e$, to their respective pieces D E, and their ends may also be tied by similar wires, if desired. 75

G designates the bottom rails of the several sections corresponding in length to rails B C, and lying in the same plane. This rail, however, does not have its ends lying beneath the 90 ends of rails B C or F F, but is shifted lengthwise and has its ends secured by wires g to the lower ends of adjoining pieces E E or D D of the fence-sections. As the adjoining pieces D or E are on opposite sides of the line of fence, 95 in order to keep the rails G vertically beneath the other horizontal rails, the adjoining ends of rails G, where they are secured to the same brace-piece, are side-lapped in proper manner to preserve the symmetrical appearance of the 100 fence, being tied together and to the side pieces by wires g , as shown.

In building the fence where only one man is employed, I propose using the standards or

rods H, (shown in Fig. 2,) which are provided with one or more adjustable collars. In using these rods, after an X-brace has been formed and one end of top rail, B, secured thereto, 5 as described, the brace is raised to a proper position and the free end of the rail supported by a similar X-brace. The rods H are then hung by their hooked upper ends on rail B, and the collars set at proper points to support 10 one end of any rail while the operator is fastening its other end in position.

When it is desired to fix the fence permanently in place, I employ the anchoring device shown in Fig. 3. This consists of disks 15 or blocks J, of any convenient form and material, tied by wires J to the lower ends of the rails A A of the X-braces and buried or sunk in the ground, so that the fence is prevented from being lifted vertically, as is evident, and enabled to withstand severe wind-storms. In 20 practice I propose employing stones for the anchor-blocks J of the fence.

Having described my invention, I claim—
In a rail fence, the combination, with the pairs of X-braces standing at right angles to 25 the line of fence, and their upper uniting-rails, B and C, supported thereby, of the inclined short pieces D, secured to one leg of each brace below its point of intersection, and the oppositely-inclined pieces E, similarly secured to 30 the remaining leg of each brace, both pieces D and E standing in the line of the fence, and the rails F and G secured to the pieces D and E and supported solely by said pieces below the points of intersection of the braces, all 35 constructed and arranged substantially as and for the purpose described.

In testimony that I claim the foregoing as my own I affix my signature in presence of two witnesses.

WILLIAM KELLY.
